(Cl. D64—12)

To all whom it may concern:

Be it known that I, Norman J. Stupell, a citizen of the United States and a resident of New York city, county of Bronx, State of New York, have invented a new, original, and ornamental Design for an Alphabet for Forming Monograms or the like, of which the following as a specification, reference being had to the accompanying drawings forming a part thereof.

Fig. 1 is a top plan view of an alphabet for forming monograms or the like showing my new design.

Fig. 2 is a front view of one of the letters shown in Fig. 1.

Fig. 3 is a side view of one of the letters shown in Fig. 1.

I claim:

The ornamental design for an alphabet for forming monograms or the like, substantially as shown.

NORMAN J. STUPELL.
